United States Patent Office

Des. 191,842
Patented Nov. 28, 1961

191,842

DECORATIVE SCREEN ELEMENT

Douglas C. Ryhn, 1913 Old Willow Road,
Northfield, Ill.

Filed Nov. 16, 1960, Ser. No. 62,869

Term of patent 14 years

(Cl. D54—2)

The figure is a perspective view of a decorative screen element embodying my new design.

I claim:

The ornamental design for a decorative screen element, substantially as shown.

References Cited in the file of this patent

UNITED STATES PATENTS

D. 122,056 Elliott ----- Aug. 20, 1940

OTHER REFERENCES

Best Metal Kraft Aluminum Railings Cat., © 1960, received May 11, 1960, page 22, grill at top of page.